UNITED STATES PATENT OFFICE

CHARLES J. BATES, JR., OF ENGLEWOOD, NEW JERSEY, ASSIGNOR TO THE MOSLER SAFE COMPANY, OF HAMILTON, OHIO, A CORPORATION OF NEW YORK

FIREPROOF JOINT CONSTRUCTION

Application filed May 6, 1931. Serial No. 535,469.

This invention relates to vaults, safes and the like and particularly to automatic means operating when heated to fill the clearance spaces between a door and the adjacent floor 5 and walls, whereby the vault or safe is rendered fireproof.

An object of the invention is to provide such means whereby fire outside the vault is precluded from entering, and fire within 10 the vault is prevented from spreading to the exterior thereof.

Another object is to provide a fireproof vault door which may yet be associated with a flat sill whereby the usual necessity of providing a difference in floor levels in order 15 to secure a fireproof condition, is obviated.

Another object is to provide means of the class described which are simple in construction and efficient in operation.

20 These and other objects are attained by the means described herein and set forth in the accompanying drawing, in which:

Fig. 1 is a horizontal cross-sectional view through a vault door constructed according 25 to the present invention, the adjacent portions of floor and wall being partially shown.

Fig. 2 is a cross-sectional view taken on line 2—2 of Fig. 1.

Fig. 3 is a cross-sectional view taken on 30 line 3—3 of Fig. 2, part being broken away.

The front wall of the vault with which the fireproof door of this invention is associated, may comprise the side vertical portions 5 of suitable grouting covered by a metallic casing 6 having spaced parallel sections 7 and 8 joined by the right angle section 9. Within the space formed exteriorly of sections 8 and 9 of the casing 6, insulation material 10 may be disposed, having the irregular casings 11 and 12 covering the outer faces thereof and adapted for interfitting association with the closed vault door, the lateral edges of which are of complementary formation. Casings 11 and 12 abut section 9 behind section 7 of casing 6, whereby an elongated shoulder or border 13 is provided on each casing 6.

The vault door 14 may be hinged, as at 15, upon a suitable support plate 16. The substantial portion of said door need not be 50 of the specific construction shown since the

fire resistance means comprised in this invention may be associated with the more usual types of doors of which the one shown is an example, as regards the general characteristics thereof. As illustrated, the door comprises a front panel 17, rear panel 18, lateral plates 19 and 20, a suitable top edge plate (not shown) and a bottom edge plate 21, angularly formed along its front portion to provide, with panel 17, a channel 22. The bottom portion of plate 21 and bottom edges of panels 17 and 18 terminate short of the flat sill 26 to permit free swinging of the door. Suitable filling or grouting 23, forming the body of the door, is disposed within the space provided by the panels and plates just described. The vault door likewise supports a suitable combination lock and mechanism 24 and a suitable bolt mechanism 25.

The fire resistance means at the front of 70 the vault door is normally housed within the channel 22. Essentially, these means consist of a non-inflammable substance 27, such as vermiculite, which expands greatly under the influence of heat. This substance is normally disposed entirely within channel 22 but should the door become heated by fire occurring adjacent to or within the vault, the substance would expand beyond the open bottom of channel 22 and wedge tightly against sill 26, being obviously adapted to conform to 75 any possible irregularities in the surface of the sill or floor. A suitable binder may be used in compounding the vermiculite, or similar substance.

The chief principle of this invention and a simple, operable adaptation thereof are explained in the preceding paragraph. However, as illustrated herein, the expansible filler is operative upon an upwadly-opening 80 channel strip 28 positioned in the channel 22 and within which the filler 27 is disposed. Strip 28 is held in place by two or more end-threaded smooth-bodied bolts 29 seated within inverted cup members 30 the out-turned 85 rims 31 of which bear against the borders of countersunk apertures 32 in the bottom 33 of strip 28. Bolt 29 is threadedly received in the upper face 34 of channel 22 and in a strip 35 disposed above and upon said face. Upon 90

bolt 29 between the head 36 thereof and the apertured base 37 of cup 30, is disposed a fusible washer 38 which normally retains the filled channel strip 28 in the positions shown in Figs. 2 and 3. Under heated conditions these washers 38 melt permitting the expanding filler 27 to force strip 28 downwardly against the sill 26, the cups 37 at this time moving downwardly along the smooth bodies 10 of bolts 29. As illustrated in Fig. 3, the side walls of channel strip 28 may be vertically slotted as at 39 for rendering the base of said strip more readily conformable to possible irregular floor or sill surfaces by action 15 of the expanding material thereon.

A fire resistance panel 40 may be positioned on the rear or inside face of the door. Such panel may be of the type set forth in the patents to Carl Bartels, No. 1,616,249 of Feb. 1, 20 1927, and No. 1,547,717 of July 18, 1925, in which the panel is supported by means 42 similar to the channel strip supporting means previously described and comprising fusible washers 43 which, upon melting, permit 25 springs 44 to urge panel 40 into abutment against elongated shoulder 18 of casings 6, thereby sealing the door at the rear.

It is obvious that the principle and construction of the expansible sealing means of 30 this invention may be adapted to any edge of a door other than at the bottom so as to coact with the jambs and lintel of a doorway or with corresponding parts of any type of structure utilizing a fireproof closure. Moreover, the expansible sealing means are adaptable for use with sills and floors other than 35 flat since, as heretofore explained, said means may be conformed to variations in such surfaces. Various modifications, within the 40 spirit and scope of the present invention, become apparent upon consideration of the means disclosed herein.

What is claimed is:

1. The combination with a positioned door 45 having a channel along its bottom edge, of means positioned in said channel and normally permitting free swinging movement of the door, said means being adapted to expand upon subjection to heat for sealing the space normally intervening between the door and the surface therebeneath.

2. The combination with a door adapted 55 for association with a flat sill and with a supporting wall providing inwardly-projecting shoulders adjacent the rear of the closed door, of means associated with the bottom and rear of the door in normally spaced relationship with the said sill and shoulders respectively, said means being adapted upon 60 subjection to heat, to move outwardly into sealing relationship with the sill and shoulders.

3. The combination with a vault door 65 associated with a flat floor surface, and having a channel formed along the bottom edge

thereof, of a channel strip providing side walls and a base, the latter having apertured countersunk portions therein, said strip being inserted, base downwardly, in said channel and held therein by means of headed bolts projecting through said apertured countersunk portions into the door and having fusible washers positioned thereon between the heads thereof and the surfaces of said countersunk portions, and means positioned in said strip and expandable upon subjection to heat, said means being adapted upon melting of said fusible washers, to move said strip downwardly into contact with the flat floor surface.

4. The combination with a vault door adapted for association with a flat sill and with a supporting wall providing inwardly-projecting shoulders adjacent the rear of the closed door, of a channel strip associated, base downwardly, with the bottom edge of the door and normally in flush countersunk relationship therewith, headed bolts projecting through the base of said strip into the door and provided intermediate the heads thereof and said base with fusible washers normally holding the strip in the position described, a panel member attached to the rear of the door by bolts and washers of the kind described, said panel member being normally disposed in spaced relationship with said inwardly-projecting shoulders in the closed position of the door, and means disposed within said channel strip and upon the said panel member and adapted, upon melting of said fusible washers, to move said strip and said panel member into sealing contact with said sill and said inwardly-projecting shoulders, respectively.

5. The combination with a door, of an expansible member attached to the door and normally adapted for spaced relationship with adjacent surfaces in the closed position of the door, and means associated with said expansible member and adapted upon heating of the door to permit movement of the expansible member into contact with surfaces adjacent the door.

6. The combination with a vault, of a door, members associated with the door and forming therewith restricted enclosed spaces, means positioning said members and normally precluding movement thereof, said positioning means comprising fusible members adapted when melted to permit limited movement of said space-forming members, and nonflammable material positioned within said enclosed spaces and adapted to expand under heat whereby, upon melting of said fusible members, to effect movement of the space-forming members outwardly of the body of the door into fire-sealing relationship with adjacent portions of the vault.

7. The combination of a door, a rear panel, means positioning the panel upon the door

and adapted upon being heated to release the panel from the door, and means associated with the bottom of the door and adapted when heated to expand outwardly of the door 5 into abutment with the surface therebeneath.

In testimony whereof, I have hereunto subscribed my name this 23rd day of April, 1931.
